UNITED STATES PATENT OFFICE.

GLENN H. CURTISS, OF BUFFALO, NEW YORK, ASSIGNOR TO CURTISS AEROPLANE AND MOTOR CORPORATION, OF BUFFALO, NEW YORK, A CORPORATION OF NEW YORK.

TWIN-FLOAT HYDROAEROPLANE.

1,306,749.

Specification of Letters Patent. Patented June 17, 1919.

Application filed August 12, 1916. Serial No. 114,531.

To all whom it may concern:

Be it known that I, GLENN H. CURTISS, a citizen of the United States, residing at Buffalo, in the county of Erie and State of New York, have invented certain new and useful Improvements in Twin-Float Hydroaeroplanes, of which the following is a specification.

This invention relates to aircraft and has reference more particularly to airplanes of the land and hydro types.

The invention is characterized by an improved arrangement of the landing gear or chassis struts. The landing gear *per se* comprises landing devices (preferably pontoons, although not necessarily) mounted beneath the supporting surface or surfaces symmetrically at opposite sides of the fuselage or body of the craft together with struts arranged to transversely diverge downwardly from the supporting surface preferably from points directly beneath the outer ends of the central panel thereof. The machine illustrated is of the biplane type. Each of the supporting surfaces of the machine is provided with a central panel. These panels terminate preferably in the longitudinal vertical plane of the longitudinal center lines of the pontoon and they are interconnected by wing posts so arranged between them that the transversely and downwardly diverging struts provide in effect substantial continuations thereof. If desired the pontoons may be braced laterally as illustrated. Other characteristics of the invention will be hereinafter pointed out and the invention precisely set forth in the appended claims.

In the drawings wherein I have illustrated the specific embodiment of my invention which I consider preferred:

Figure 1 is a perspective view of the complete machine;

Fig. 2 is a side elevation;

Fig. 3 is a front elevation with the supporting planes partly broken away;

Fig. 4 is a top plan view similarly characterized;

Fig. 5 is a diagrammatic view illustrating the pontoon pumping system;

Fig. 6 is a view illustrating diagrammatically the pontoon pumping system from a different angle, and

Fig. 7 is a detail view of the tail pontoon.

Like numerals of reference designate like

or corresponding parts throughout the several views.

The body of the craft, designated in its entirety by the numeral 10, is constructed in fuselage form and equipped with cockpits 11 tandemly arranged both aft of the center of gravity of the machine to counterbalance in part the weight of the propelling power plant located ahead thereof and designated 12. Staggered superposed planes 13 of unequal spread constitute with ailerons 14, elevator flaps 15, a rudder 16, a vertical stabilizer 17, and a horizontal stabilizer 18, the several aerofoils essential to flight. The detail construction and arrangement of these aerofoils with respect to the fuselage and to each other is immaterial in so far as the remaining structural features are concerned.

Upon reference to Fig. 3, it will be noted that each supporting plane 13 is made up of connected sections or panels and that the central wing panel of each, designated 13', is of a size to overhang or extend laterally considerably beyond the sides of the fuselage 10. This particular arrangement affords a better base or support for the flotation bodies or main pontoons. The pontoons, of which there are two, each designated in its entirety by the numeral 19, constitute with appropriate struts the undercarriage or landing gear for the machine.

Each pontoon 19 is of a substantially streamline form, pointed fore and aft, and equipped with an underneath hydroplaning surface of suitable design. From the prow aft, the hydroplaning bottom of each pontoon extends downwardly and rearwardly to a point 20 where it extends rearwardly substantially horizontally to the stern. The hydroplaning bottom of each pontoon I have designated 21. In machines of this character it is preferred that the center of hydroplane lift be located ahead of the center of pressure and that the pontoons for the major part extend forwardly beyond a line in the vertical plane thereof.

Inverted V-arranged struts 22 depend, in the vertical plane of central wing panel wing posts 23, from the underneath surface of the lower supporting plane to the respective pontoons, the diverged terminals of the mating struts engaging with the pontoons adjacent opposite sides thereof and as best illustrated in Figs. 2 and 3. A forward sin-

gle diagonal strut 24 is positioned intermediate the forward inverted V-arranged struts of each pontoon to brace the forwardly extending portion of the pontoon to the lower 5 supporting plane and to the point where the forward inverted V-arranged struts engage. Lateral diagonal struts 25 diverge from the under side of the fuselage to the opposed pontoons. These struts not only brace the 10 pontoons against lateral displacement but afford with the inverted V-arranged struts 22 a relatively wide base and accordingly a perfectly rigid support for the pontoons.

The pontoons, as illustrated, are mounted 15 in a horizontal plane beneath and at opposite sides of the fuselage (as suggested) in the approximate vertical plane of the central wing panel terminals. The impact in landing is thus transmitted directly, uniformly, 20 opposite and diagonally to the biplane cell formed by the central wing panels. Appropriate wiring 26 interconnects, and with the wing posts 23, braces the central wing panels.

25 Hydroaeroplanes of the character disclosed, unless balanced perfectly, have a tendency, when alighting or hydroplaning, to fall by the after end. In so doing, the empennage comes in contact with the surface 30 of the water and if unchecked in its falling movement is partly immersed. Many machines, to obviate this contingency, are provided with what are known as tail pontoons. Such pontoons, heretofore, in structure and 35 form possess characteristics of the main pontoons and accordingly in flight offer resistance entirely disproportionate to the useful function which they serve. By the present invention it is proposed to materially de- 40 crease the head resistance and at the same time prevent immersion of the empennage while landing or hydroplaning. The tail pontoon, designated in its entirety by the numeral 27, designed for this purpose is 45 characterized by a longitudinal cross sectional configuration generally complementary to the underneath tail end formation of the fuselage and the general shape of a pyramid. In length, the tail pontoon is incomparable 50 with the main pontoons 19. From its forward end aft, the underneath surface of the tail pontoon inclines downwardly and rearwardly in much the same manner as the forward hydroplaning surface of the main pontoon except that the chines or lower marginal edges of the tail pontoon converge rearwardly in streamline form to the tail post. 55 The stern post ordinarily located at the extreme after end of the fuselage structure is continued beyond the underneath surface thereof in the present instance to serve as the stern post of the tail pontoon. The sides 60 of the pontoon in reality are but continuations of the vertical sides of the fuselage beneath and against which the tail pontoon is

secured or made as an integral part. Braces 28 extend diagonally from the horizontal stabilizer 18 to the stern post of the tail pontoon.

As a further aid in elevating the tail end 70 of the machine while hydroplaning I have equipped the tail pontoon with a flexible paddle. This paddle is designated 27' and made secure against the underneath surface of the tail pontoon to extend slightly rearwardly therebeyond in prolongation of the integral hydroplaning surface formed upon the pontoon itself. In action the paddle is designed to flex and to a certain extent cushion the impact occasioned when alighting or hydroplaning. The stern post beneath which the paddle is arranged affords an axis about which it is designed to flex or oscillate. Moreover, the paddle acts effectively as a guard for the tail pontoon—i. e., 85 it prevents contact of the pontoon with the ground in the event of operation upon or over exceedingly shallow water.

In referring to the drainage system for the main pontoons illustrated diagrammatically in Figs. 5 and 6, 29 designates a suction pump either hand operated or power driven. Leads (preferably flexible) extend from the interior of the fuselage and from each side thereof, one to each of several 90 watertight compartments formed interiorly of the main pontoons. The pontoons, as indicated, are divided both transversely and longitudinally into non-communicating compartments by watertight bulkheads 30. 100 Each pontoon is preferably divided into six compartments whereby in the drainage system twelve leads are required. From the fuselage to the pontoons, the leads extend, six at each side, contiguous to the forward 105 diagonal struts 25 with which they are streamlined and to which they are secured by any suitable means. In draining the pontoons it is but necessary that the pump be operated after having first been attached 110 to the lead extending from the compartment required to be drained.

While in the foregoing there has been illustrated in the drawings and described in the specification, such combination and arrangement of elements as constitute the preferred construction or embodiment of the invention, it is nevertheless desired to emphasize the fact that an interpretation of the invention should only be conclusive 115 when made in the light of the subjoined claims.

What is claimed is:

1. In an aircraft, a fuselage, pontoons mounted beneath and symmetrically at opposite sides of the fuselage, superposed supporting surfaces each including a central panel, the length of the central panels being such that the ends thereof terminate in the longitudinal vertical plane of the respective 120

longitudinal center lines of the pontoons, wing posts interconnecting the central panels at the ends thereof, and chassis struts arranged to diverge symmetrically downwardly from the bottom supporting surface directly beneath the said wing posts.

2. In an aircraft, a fuselage, pontoons mounted beneath and symmetrically at opposite sides of the fuselage, superposed supporting surfaces each including a central panel, the length of the central panels being such that the ends thereof terminate in the longitudinal vertical plane of the respective longitudinal center lines of the pontoons,

10 15 wing posts interconnecting the supporting surfaces at their ends, and chassis struts inverted V-arranged, the apices of the inverted V-struts engaging directly beneath and in alignment with said wing posts.

20 25 3. In an aircraft, a fuselage, pontoons mounted beneath and at opposite sides of the fuselage, superposed supporting surfaces each including a central panel, the length of the central panels being such that the ends thereof terminate in the longitudinal vertical plane of the respective longitudinal center lines of the pontoons, wing posts interconnecting the central panels at their ends, chassis struts arranged to diverge symmetrically downwardly from the bottom supporting surface directly beneath said wing posts, and means inclining upwardly and inwardly from the respective pontoons for connection with the fuselage.

30 35 4. In an aircraft, a fuselage, pontoons mounted beneath and at opposite sides of the fuselage, superposed supporting surfaces including central panels of a length sufficient to extend considerably beyond the sides of the fuselage, wing posts interconnecting the panels at their ends, chassis struts arranged to converge upwardly from the pontoons for connection with the central panel of the lower supporting surface in alignment with the wing posts, and wiring for the central panels arranged to extend inwardly and upwardly from the foot of each wing post to brace the lower center panel at the points where the chassis struts engage.

40 45 5. In an airplane, a fuselage, a supporting surface including a central panel, landing devices mounted beneath the supporting surface and symmetrically at opposite sides of the fuselage with their longitudinal center lines in the longitudinal vertical plane of the ends of the panel, and struts transversely downwardly divergent from the ends of the panel for the support of the landing devices.

50 55 6. In an airplane, a fuselage, a support-

ing surface including a central panel, landing devices mounted beneath the supporting surface and symmetrically at opposite sides of the fuselage with their longitudinal center lines in the longitudinal vertical plane of the ends of the panel, and struts transversely downwardly divergent from the ends of the panel for the support of the landing devices.

7. In an airplane, a fuselage, a supporting surface including a central panel, landing devices mounted beneath the supporting surface and symmetrically at opposite sides of the fuselage with their longitudinal center lines in the longitudinal vertical plane of the ends of the panel, struts transversely downwardly divergent from the ends of the panel for the support of the landing devices, and means for bracing the landing devices against laterally directed shocks.

8. In an airplane, a fuselage, superposed supporting surfaces including a lower central panel, wing posts mounted at the ends of the panel to interconnect the supporting surfaces, landing devices mounted beneath the supporting surfaces symmetrically at opposite sides of the fuselage with their longitudinal center lines in the longitudinal vertical plane of the ends of the panel, and transversely divergent strut connections between the landing devices and said panel, the upper strut ends engaging the panels respectively directly beneath said posts.

9. In an aircraft, a fuselage, a tail pontoon of a construction designed for fitting engagement close up under the tail end of the fuselage, and a means continuing the underneath surface of the pontoon rearwardly beyond the stern post of the machine.

10. In an aircraft, a fuselage, a tail pontoon of a construction designed for fitting engagement close up under the tail end of the fuselage, and a flexible means continuing the underneath surface of the tail pontoon rearwardly beyond the stern post of the craft, the stern post directly engaging with said means to afford an axis of flexion.

11. In an aircraft, a fuselage, and a tail pontoon mounted close up under the tail end of the fuselage, said pontoon in horizontal longitudinal section being substantially complementary to the corresponding section of that portion of fuselage beneath which it is mounted; the sides of the fuselage and the sides of the pontoon being vertically flat and in continuance, one of the other.

In testimony whereof I affix my signature.

GLENN H. CURTISS.
